UNITED STATES PATENT OFFICE.

ISAAC W. LITCHFIELD, OF BOSTON, MASSACHUSETTS, ASSIGNOR TO LAMSON CONSOLIDATED STORE SERVICE COMPANY, OF NEWARK, NEW JERSEY, A CORPORATION OF NEW JERSEY.

CARRIER FOR PNEUMATIC-DESPATCH-TUBE APPARATUS.

No. 923,280.

Specification of Letters Patent.

Patented June 1, 1909.

Application filed July 11, 1905. Serial No. 269,148.

To all whom it may concern:

Be it known that I, ISAAC W. LITCHFIELD, of Boston, in the county of Suffolk and State of Massachusetts, have invented certain new and useful Improvements in Carriers for Pneumatic - Despatch - Tube Apparatus, of which the following is a specification.

My invention relates to improvements in carriers adapted for use in pneumatic despatch tube apparatus, and its object is to produce an indicating device to indicate to the operator at the central station to which of the substations the carrier is to be sent.

In the accompanying drawings which illustrate a construction embodying my invention, Figure 1 is a perspective view of the carrier. Fig. 2 is a longitudinal sectional view through the carrier. Fig. 3 is a cross sectional view taken on the line Y—Y Fig. 2 looking toward the buffer. Fig. 4 is a cross sectional view on the line X X Fig. 2.

Like letters of reference refer to like parts throughout the several views.

In the head of the carrier A is a buffer of yielding material such as felt which is secured to the plate C inside of the carrier by the bolts D. Between the end of the head of the carrier and the buffer B is a flexible washer or leather ring E on which is placed the arrow E'. This washer is of greater diameter than head A and acts as a skirt to prevent leakage of air by said head. The ring E is secured to the buffer head B by the pins G which when the parts are assembled rest on the end of the head of the carrier as shown in Fig. 2. The buffer head B, plate C and leather ring E all rotate together so that the pointer or arrow E' can be moved opposite any desired number to represent the substation to which the carrier is to be sent. The casing of the carrier adjacent to the head is provided with any desired number of characters to indicate the corresponding number of substations in the system and may be used to send parcels or messages to any one of the substations, as it is only nec-

essary for the attendant to adjust the pointer or arrow and indicate the desired station before inserting the carrier into the tube for transmission to the central station, from which central station the carriers are despatched in tubes leading to the station indicated by the number opposite the pointer.

The rear end of the carrier is provided with a flange L against which rests the felt ring K, which when placed in the position shown in Fig. 2, is held against displacement by the metal ring J sprung into the groove H, and when the ring K becomes worn from use, the metal ring is sprung from the groove and the felt ring removed and a new one substituted, after which the ring is sprung back again and holds the new felt ring in place. This feature is of decided advantage over the old construction where a fiber ring was placed permanently on the rear of the carrier. This improved felt ring and metal ring are not claimed as a part of this invention as the same form part of an application about to be filed by Edward G. Thomas of New York city.

Having thus described the nature of my invention and set forth a construction embodying the same, what I claim as new and desire to secure by Letters Patent of the United States is:

In a carrier for pneumatic despatch tube apparatus, the casing having station-indicating characters displayed on its periphery, a rotatable head on said carrier, and a flexible washer carried by said head of greater diameter than said casing having a pointer thereon to designate any one of the station-indicating characters as the head is rotated.

In testimony whereof, I have signed my name to this specification in the presence of two subscribing witnesses, this sixth day of July A. D. 1905.

ISAAC W. LITCHFIELD.
